UNITED STATES PATENT OFFICE.

FREDERICK MAX PORITZ, OF NEW YORK, N. Y., ASSIGNOR TO STAR CHANDELIER COMPANY, INC., OF NEW YORK, N. Y., A CORPORATION OF NEW YORK.

DESIGN FOR AN ELECTRIC-SOCKET COVER.

Application filed October 12, 1923. Serial No. 7,477. Term of patent 3½ years.

To all whom it may concern:

Be it known that I, FREDERICK MAX PORITZ, a citizen of Germany, residing at New York, in the county of New York and State of New York, have invented a new, original, and ornamental Design for an Electric-Socket Cover, of which the following is a specification, reference being

had to the accompanying drawing, forming part thereof.

The figure is a side view of an electric socket cover, showing my new design.

I claim—

The ornamental design for an electric socket cover, as shown.

FREDERICK MAX PORITZ.
